UNITED STATES PATENT OFFICE.

ALBERT T. STRAUCH, OF NEW YORK, N. Y.

PIANISSIMO DEVICE FOR GRAND-PIANO ACTIONS.

1,157,262.

Specification of Letters Patent.

Patented Oct. 19, 1915.

Application filed May 26, 1915. Serial No. 30,492.

To all whom it may concern:

Be it known that I, ALBERT T. STRAUCH, a citizen of the United States, and a resident of New York city, in the county and State of New York, have invented certain new and useful Improvements in Pianissimo Devices for Grand-Piano Actions, of which the following is a specification.

This invention relates to a pianissimo device more particularly adapted for grand piano actions that may be played by hand as well as by mechanical means. The construction is such that upon the depression of the soft pedal, either during manual or mechanical playing, lost motion is prevented and a substantially uniform touch is maintained.

In the accompanying drawing: Figure 1 is a side view, partly in section, of a grand piano action embodying my invention, showing the normal position of the parts; Fig. 2 is a similar view showing the position of the parts with the soft pedal depressed, and Fig. 3 a plan of part of the action.

The capstan 1 of the manually actuated key 2, operably engages an upper oscillative member of lever 3, in suitable manner, the drawing showing oscillative member 3 to be provided with a rocker 4, that is adapted to rest upon the capstan. Oscillative member 3 is attached to and forms part of the action, it being pivoted at its front end to a flange 5 of a rail 6 of the action frame, while it extends with its rear end a distance beyond key 2, and is here furnished with a button 7, which is engaged by the sticker 8 of a pneumatic or other self playing mechanism. From oscillative member 3 there projects upwardly a flange 9 to which is pivoted at 10 a forwardly extending lost-motion lever 11, which has an inclined rear section and a substantially horizontal front section or foot that joins the rear section at an obtuse angle, and is adapted to be supported directly on oscillative member 3, above capstan 1. Upon the foot rests the knuckle 12 of a conventional grand action support 13 which is pivoted at its rear end to a flange 14 of action rail 15. Support 13 carries a repetition lever 16, and a jack 17 adapted to engage hammer shank 18, as usual.

The hammer shank is adapted to be supported by the hammer rest rail 19, which by arms 20 is pivotally connected to flanges 21 of the action bracket 22. From rail 19 extends rearwardly a finger 23 which is ac-

tuated by the lifter 24, of the soft pedal (not shown). Arms 20 have longitudinal slots 25 adjustably engaged by clamp screws 26 of forked members 27 to which are pivoted at 28 hangers 29. The lower ends of these hangers engage apertured blocks 30 which are clamped to the hangers by screws 31. Blocks 30, are pivoted to a pair of arms 32 which are hung at their rear ends in the action bracket as at 33, while they carry at their front ends, a lost motion rod 34. This rod extends transversely over the oscillative members 3 and is located a distance above the same and in front of the lost motion levers 11. From the free end of each lever 11 projects forwardly, an upwardly inclined finger or extension 35, carrying a pad 36 which is adapted to be engaged by rod 34.

The operation is as follows: When the instrument is played by hand under normal conditions, the movement imparted to key 2, will be transmitted by capstan 1 to oscillative member 3, and thence directly to foot of lever 11, which by support 13, actuates the conventional parts of the action. When the instrument is played by mechanical means, likewise under normal conditions, the sticker 8 will operate oscillative member 3, so as to again actuate through foot of lever 11 and support 13 the conventional parts of the action (Fig. 1). When the soft pedal is depressed to raise rail 19, the resulting upward swing of arms 20, will by hangers 29 and arms 32 cause lost motion rod 34 to be raised, so as to tilt lost motion lever 11 upward by finger 35, and thus open up a gap between the foot of said lever and the oscillative member 3 (Fig. 2). If now the instrument is played either by hand or mechanically, motion will be transmitted from oscillative member 3, through flange 9, and pivot 10, to the lever 11, and thence to the support 13, the transmission of motion no longer taking place directly from said oscillative member to the foot of the lever as heretofore. In this way lost motion is prevented, and the normal touch is substantially maintained.

Owing to the adjustment between arms 20 and hangers 29, the degree to which rod 34 may be raised by the depression of the soft pedal is accurately regulable.

I claim:

1. In a grand piano action, a frame, a key, an oscillative member pivoted to the frame and operable by the key, a lost motion

lever carried by the oscillative member, a support engaging said lever, a hammer rest rail, and means operable by said rail for tilting the lost motion lever.

5 2. In a grand piano action, a frame, a key, an oscillative member pivoted to the frame and operable by the key, a mechanically-actuated sticker engaging the oscillative member, a lost motion lever carried 10 by the oscillative member, a support engaging said lever, a hammer rest rail, and means operable by said rail for tilting the lost motion lever.

15 3. In a grand piano action, a frame, a key, an oscillative member, pivoted to the frame and operable by the key, a flange on the oscillative member, a lost motion lever pivoted to said flange and having a foot adapted to rest on the oscillative member, a support 20 engaging said lever, a hammer rest rail, and means operable by said rail for tilting said lever.

25 4. In a grand piano action, a frame, a key, an oscillative member pivoted to the frame and operable by the key, a lost motion lever carried by said oscillative member, a support engaging the lever, a pair of pivoted arms, a hammer rest rail carried by said arms, hangers depending from the arms, a lost motion rod 30 operably connected to the hangers, and means on the lever for engaging said rod.

35 5. In a grand piano action, a frame, a key, an oscillative member pivoted to the frame and operable by the key, a lost motion lever carried by said oscillative member, a support engaging the lever, a pair of pivoted arms, a hammer rest rail carried by said arms, hangers depending from the arms, a 40 lost motion rod operably connected to the

hangers, and a finger extending forwardly from the lever and engaging the rod.

6. In a grand piano action, a frame, a key, an oscillative member pivoted to the frame and operable by the key, a flange on 45 the oscillative member, a lost motion lever pivoted to said flange and composed of an inclined section and a foot that is adapted to be supported on the oscillative member, a support engaging said foot, a hammer rest 50 rail, and means operable by said rail for tilting the lost motion lever and thereby raising its foot off the oscillative member.

7. In a grand piano action, a frame, a key, an oscillative member pivoted to the frame and operable by the key, a flange on 55 the oscillative member, a lost motion lever pivoted to said flange and having a foot adapted to engage the oscillative member, a first pair of pivoted arms, a hammer rest 60 rail carried by said arms, hangers depending from the arms, a second pair of pivoted arms engaged by the hangers, a lost motion rod carried by said second pair of arms, and means on the lever for engaging the rod. 65

8. In a grand piano action, a frame, a key, an oscillative member pivoted to the frame and operable by the key, a flange on 70 the oscillative member, a lost motion lever pivoted to said flange and having a foot adapted to engage the oscillative member, a first pair of pivoted arms, a hammer rest rail carried by said arms, a pair of hangers, means for adjustably securing said hangers to said arms, a second pair of pivoted arms 75 engaged by the hangers, a lost motion rod carried by said second pair of arms, and a finger extending forwardly from the lever and engaging the rod.

ALBERT T. STRAUCH.
